US00D897746S

(12) **United States Design Patent** (10) Patent No.: **US D897,746 S**
(45) Date of Patent: ** Oct. 6, 2020

(54) **PRODUCT DISPLAY UNIT**

(71) Applicant: **Apple Inc.**, Cupertino, CA (US)
(72) Inventors: **Jean-Marc Gady**, Los Altos, CA (US);
Seung Chae Kang, New York, NY (US); **Gabriel J. Lamb**, Burlingame, CA (US); **Adrian E. Magrina**, San Francisco, CA (US); **Indhu V. Solayappan**, Sunnyvale, CA (US); **Moritz Wilsberg**, Rheinbreitbach (DE)

(73) Assignee: **Apple Inc.**, Cupertino, CA (US)

(**) Term: **15 Years**(21) Appl. No.: **29/744,096**(22) Filed: **Jul. 27, 2020****Related U.S. Application Data**

(63) Continuation of application No. 29/693,874, filed on Jun. 5, 2019, now Pat. No. Des. 891,158.
(51) **LOC (12) Cl.** **06-06**
(52) **U.S. Cl.**
USPC **D6/682.1**
(58) **Field of Classification Search**

Primary Examiner — Kelley A Donnelly*(74) Attorney, Agent, or Firm* — Sterne, Kessler, Goldstein & Fox P.L.L.C.(57) **CLAIM**

The ornamental design for a product display unit, as shown and described.

DESCRIPTION

FIG. 1 is a top front perspective view of a product display unit showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the product display unit that form no part of the claimed design.
